UNITED STATES PATENT OFFICE.

GEORGE H. EDDY, OF FOSTER, WASHINGTON.

GOLF TEE.

Application filed April 6, 1926. Serial No. 100,144.

This invention relates to an improvement in golf tees, and is designed to provide a golf tee which will at the same time serve the purpose of a writing implement for marking the scores.

The invention is designed to utilize a short length of pencil, the upper end of which is hollowed to receive and support the golf ball, the lead of the pencil serving as the 10 penetrating point for the insertion of the tee in the ground and the sharpening of the wood of the pencil to expose the lead providing the necessary conical formation essential for the insertion of the tee.

15 The invention is illustrated in the accompanying drawings, in which:

Fig. 1 is an elevation, partly in section, of the preferred form.

Fig. 2 is a similar view showing the tee 20 reinforced.

Fig. 3 is a similar view showing a modified form of reinforce.

In carrying out the invention, a short length of pencil 1 is sharpened on graduated 25 lines to expose the lead 2, the sharpening being preferably, though not necessarily, throughout the full length of the pencil section. The upper end of the pencil section is hollowed, as at 3 to provide for the support of the ball.

In use, the conical pencil section is forced into the ground in the usual manner or application of artificial tees, and the ball supported in the hollow 3 for the usual driving

function. If desired, and as indicated in Fig. 2, the formed pencil section may be 35 coated with heavy shellac as at 4, or other similar material to protect the halves of the pencil section against separation and to further protect the body of the pencil against 40 wear. If a more positive reinforce is desired, the conical pencil section may be wrapped as at 5 by cord or wire to increase 45 the life of the article in use and under possible contact from the driver. The improved tee is designed to provide in a single implement a convenient tee for the golfer's use, and at the same time a writing implement by 50 which the scores may be entered. It not infrequently happens that the golfer will be 55 without adequate means to enter his score, or if provided with a pencil and also one or more of the artificial tees, will be handicapped by the necessity of carrying a number of different implements. With the present tee, the writing implement is an integral 60 part of the tee and thus through the use of the single device, the golfer has at his command, a convenient and really desirable tee and a writing implement.

65 What I claim is:

A pencil having a wooden envelope of conical form throughout and the upper end formed with a rounded depression and a reinforce wrapping for the envelope.

65 In testimony whereof I affix my signature.

GEORGE H. EDDY.
